UNITED STATES PATENT OFFICE.

FREDERICK CARLISLE, OF FRANKLIN, ASSIGNOR OF PART TO CHARLES E. HOFFMAN, OF JERSEY CITY, NEW JERSEY.

APPARATUS FOR ABSORBING GASES.

SPECIFICATION forming part of Letters Patent No. 395,691, dated January 8, 1889.

Application filed December 17, 1887. Serial No. 258,165. (No model.)

To all whom it may concern:

Be it known that I, FREDERICK CARLISLE, a citizen of the United States, residing at Franklin, Essex county, New Jersey, have invented 5 certain new and useful Improvements in Apparatus for the Absorption of Gases, fully described and represented in the following specification and the accompanying drawings, forming a part of the same.

10 My invention consists in an improved construction for exposing an absorbing-fluid to the action of a gas.

The construction consists in a series of sloping conductors provided each with a receptacle at one end, the receptacle being open at one side, and thereby adapted to overflow at the end of the conductor to discharge the fluid upon its under side, the fluid dripping from the lower end of each conductor of the 20 series into the receptacle of the succeeding conductor, and thus being distributed in turn over the under sides of all the conductors.

It also consists in a manifold arrangement 25 of the series of conductors by which the gas is forced to rise simultaneously through a series of parallel inclined spaces, where it is brought into the most intimate contact with the gases.

These constructions are shown in the annexed drawings, in which—

Figure 1 is a plan, partly in section on line $x' x'$ in Fig. 2, of a casing for several series of conductors with an attached vaporizing-furnace and gas-channel. Fig. 2 is a vertical 35 section of the same on line xx in Fig. 1. Fig. 3 is a transverse section on line yy in Fig. 5 of part of the casing and one of the conductors upon a much larger scale; Fig. 4, a transverse section of a conductor of alternative 40 construction; Fig. 5, a longitudinal section of the receptacle upon the upper end of the conductor upon a larger scale than Fig. 1.

In Figs 1 and 2, A is the casing inclosing a chamber, A', containing a series of conductors, $b b' b^2 b^3 b^4 b^5$. These conductors are each slightly inclined to promote the flow of the fluid along its under surface, and are provided each with a small receptacle or drip-cup, c, at its upper end, the receptacles of the 45 upper series being supplied with the absorbing-fluid by pipes d from a tank, d' .

Each receptacle is open at the upper end of the conductor and incloses the fluid upon all other sides, so that the liquid which accumulates therein runs over the end of the 55 conductor, which is preferably concave, as at e in Fig. 1, to direct the fluid to its middle. The fluid adheres to the under side of the conductor, as it is often seen to do upon the under side of sloping roof-beams when the 60 roof leaks, and may be directed from the lower end of the conductor into a similar receptacle by a lip, f . The fluid is thus transferred from one series of conductors to the other, running along their under surfaces 65 throughout its entire course, and finally dripping from the lower ends of the last series into a suitable tank or receptacle, E, from which it may be drawn by a cock, F.

At G is shown a furnace containing a sulphur-pot, h , and a niter-pot, i , to generate the fumes used in the production of sulphuric acid. From the furnace the gas is shown conducted through a bent passage, J, and nozzle J' into the lower part of the chamber A', a 75 steam-jet being shown at k to facilitate the discharge of the gases thereto.

A pipe, m , is shown conducted from the upper part of the chamber to the passage J adjoining the furnace, and a steam-pipe, n , is 80 shown connected therewith to induce a current of the gases which have been uncombined with the fluid in the chamber, that they may be returned again to the lower part of the chamber through the nozzle J'.

The apparatus for generating and supplying the gas to the chamber forms no part of my present invention; but it will be seen that when introduced therein it is forced by the manifold arrangement of the several 85 series of inclined conductors to flow simultaneously into the series of parallel spaces o between the several conductors, its upper passage being obstructed in all other directions by the approximation of the conductors to 90 the walls of the chamber upon every side. The gases therefore pass between and beneath the several conductors, and when they reach the upper ends of the lower series flow naturally into the spaces of the series above, 95 and are thus kept in the closest contact with the fluid exposed upon their under surfaces.

In Fig. 3 is shown a transverse section of one of the conductors on line $z z$ in Fig. 5, the conductor being formed of sheet-lead and arranged to fill the entire space between the 5 side walls of the casing A.

To confine the liquid to the conductors and prevent its discharge against the side walls of the casing, each conductor is preferably grooved at its outer edges, as shown by the 10 bending of the sheet-lead at the angles p , to lower the conducting-surface b below the ribs q , by which the conductor is sustained upon the casing A.

In addition to the grooves or angles p , formed 15 at the edges of the conductors, longitudinal grooves may be formed intermediate to those at the sides, as shown in Fig. 4, by which means the liquid may be prevented from running to one edge of the conductor when supplied to its under surface, the intermediate grooves, p' , confining the liquid to the several tongues which exists between them upon the conductor.

The conductors are in practice inclined 20 about one and one-half inch to each foot, which produces a suitable velocity in the current.

I am aware that heretofore perforated plates have been superposed upon one another and 25 connected by hydraulic lutes around their edges, the openings being flanged to prevent the discharge of the liquid through the opening until it had accumulated to a certain depth upon the upper surface of the plate, and the 30 lower surfaces of the plates being inclined to diffuse the fluid upon the same. I do not therefore claim, broadly, the mere exposure of the fluid upon the under surface of a conductor, but have devised a construction which 35 may be cheaply made of wood and lead, and adapted to bring the gas into the closest possible contact with the under surfaces of the conductors, as I have shown in the parallel 40 spaces o in Fig. 2 of my drawings. By the 45 construction shown in Figs. 3 and 4 I also prevent the liquid from flowing from the conductors upon the sides of the chamber in which they are retained, and by the provision 50 of the receptacle c at the upper ends of the conductors and the arrangement of the manifold series of conductors, with their lower ends over a series of such receptacles, I am 55 enabled to greatly increase the surface of the conductors within a chamber of given capacity; while the gas is forced to divide into thin films to pass from the lower part of the chamber upward through the narrow spaces o .

The gas is necessarily introduced at the

bottom of the chamber, as it is desirable to have it move in the opposite direction from the current of absorbing-fluid, which, by its gravity, necessarily flows downward from the point where it is supplied.

I am aware of the state of the art in United States Patents Nos. 265,974, 309,968, 180,901, 60 and 284,817, and wholly disclaim the constructions shown therein.

What I claim and desire to secure is—

1. In an apparatus for absorbing gases by a liquid, the combination, with the narrow 70 chamber A' , of a series of longitudinal inclined conductors arranged one above another and provided each with a receptacle upon its upper end, the receptacle being open upon one side toward the higher end of the conductor, and thereby adapted to discharge the 75 fluid over the end of the conductor upon its under side, and the fluid being delivered from the lower end of one conductor into the receptacle at the upper end of the next conductor throughout the series, substantially as 80 herein set forth.

2. In an apparatus for absorbing gases by a liquid, the combination, with the narrow 85 chamber A' , of a series of longitudinal inclined conductors arranged one above another and provided each with a receptacle upon its upper end, the receptacle being open upon one side toward the higher end of the conductor, and thereby adapted to discharge the 90 fluid over the end of the conductor upon its under side, and the conductor being grooved or bent adjacent to the casing of the chamber A' , to confine the fluid to the under side of the conductor, as and for the purpose set forth. 95

3. In an apparatus for absorbing gases by a liquid, the combination, with the narrow 100 chamber A' , of several series of sloping conductors arranged one above the other, with the narrow spaces o between the several conductors, each conductor being provided with a receptacle at its upper end, such receptacle being open upon one side toward the higher end of the conductor to discharge the fluid over the 105 end of the conductor upon its under side, and the lower ends of the conductors being arranged over the receptacles of the conductors beneath the same, as and for the purpose set forth.

In testimony whereof I have hereunto set 110 my hand in the presence of two subscribing witnesses.

FREDERICK CARLISLE.
